RAILWAY TRAFFIC CONTROLLING APPARATUS
Clifford D. Ihrig, Penn Township, Allegheny County,
Pa., assignor to Westinghouse Air Brake Company,
Wilmerding, Pa., a corporation of Pennsylvania
Filed Apr. 21, 1958, Ser. No. 730,022
4 Claims. (Cl. 246—34)

My invention relates to railway traffic controlling apparatus and particularly to an arrangement of apparatus for use in a single track, two direction, stretch of railway track provided with normally energized reversible coded track circuits with reverse code supplied to the rails of the track during the off periods of the normal code.

In railway traffic control systems, manually controlled signals for governing the movements of trains over a stretch of railway track are sometimes separated by a considerable distance. Under such circumstances it is usually expedient to provide one or more sets of automatic intermediate signals within said stretch of track in order to allow for following train movements and thereby expedite the movement of trains through the stretch. In such a stretch of railway track where coded track circuits are used in lieu of line conductors for control of the signals, it is sometimes desired to supply reverse code to the rails, during the off periods of the normal code, to effect approach lighting of the intermediate signals and thereby conserve power, or to obtain approach application of cab signal energy to the rails at the intermediate signal locations.

Under the above described conditions, means must be provided at the intermediate signal locations to distinguish whether normal code or reverse code is being received from the rails of the track stretch in order to prevent an intermediate signal from clearing against an opposing train movement. It is accordingly one object of my invention to provide an arrangement of apparatus at each intermediate signal location to obtain such distinction between normal and reverse code.

Other objects and characteristic features of my invention will become apparent as the description proceeds.

In accomplishing the foregoing objects of my invention, I employ at each intermediate signal location a slow release relay for distinguishing the code received. This relay is energized when normal code is received over the rails from one direction and is retained energized while reverse code is being received over the rails from the opposite direction. Contacts of this relay are used for prevention of clearing the improper intermediate signal, as will become apparent hereinafter in this description.

I shall describe one form of apparatus embodying my invention, and shall then point out the novel features thereof in claims.

Referring to the accompanying drawings, FIGS. 2 through 5, when arranged as shown in FIG. 1, illustrate a stretch of railway track over which trains may move in either direction, and provided with normal and reverse coded track circuits employing apparatus of my invention. FIG. 2 illustrates the left or westbound end of the stretch of railway track provided with a signal 1EG, manually controlled as will hereinafter be described, and associated apparatus for controlling the movement of trains in an eastwardly direction over said track stretch. FIG. 4 illustrates the right or eastward end of the track stretch and a manually controlled signal 2WG and associated apparatus for controlling train movements in a westwardly direction over the stretch. FIGS. 3 and 5 illustrate a set of automatic signals and associated apparatus located intermediately between said controlled signal locations. These intermediate signals are designated

2

1WG and 2EG and control train movements past said location in westwardly and eastwardly directions, respectively.

The stretch of railway track between signals 1EG and 2WG is divided into a westward and an eastward track section designated 1T and 2T, respectively. Track section 1T extends from signal 1EG to the intermediate signal location and track section 2T extends from said location to signal 2WG. Each of these track sections is provided with coded track circuits, the structure and operation of which will be made apparent as the description proceeds. However, for present purposes it should be pointed out that track relays 1ETR, 1WTR, 2ETR, and 2WTR are associated with the rails of the track 15 stretch at the west end of track section 1T, the east end of track section 1T, the west end of track section 2T, and the east end of track section 2T, respectively. These track sections are separated from each other, and from the stretches of track to the west and east of signal locations 1EG and 2WG, respectively, by insulated rail joints shown in the drawings in the conventional manner by lines drawn perpendicularly across each of the lines representing the rails of the track stretch.

It is believed expedient to point out at this time 25 that energy for the operation of the apparatus at each signal location, except the coded track circuits, is furnished by a suitable source of direct current such as a battery of proper voltage and current. For the purposes of simplicity these sources are not shown in the drawings, but their positive and negative terminals are identified by the reference characters B and N, respectively. Energy for operation of the coded track circuits are shown in the drawings, in the conventional manner, as batteries designated 1TBW, 1TBE, 2TBW and 2TBE located at signal locations 1EG, 1WG, 2EG and 2WG, respectively.

The above named track relays as well as several other relays shown in the drawings have the letters CF shown in the rectangles representing the windings of the relays. 40 These letters are used to designate code following relays, that is relays which are picked up when a code pulse is supplied to their windings and released when the code pulse is removed. The contacts of these relays are shown with their movable members in both up and down 45 positions with one position being represented by a solid line and the other position being represented by a dotted line. These contacts are shown in this manner to indicate that their associated relay is a code following relay and the solid line represents the normal condition of the associated relay. That is, if the solid line represents the up position of a contact its associated relay is following normal code, and if the solid line represents the down position of a contact its associated relay is not following normal code. As previously stated the track circuit system employed with my invention is a normally energized reversible coded track circuit system and is normally coding in the direction from east to west as will be more fully outlined further on in this specification. Therefore, the code following relays with their contacts shown 50 in the up position, that is with the solid lines of the movable members of the contacts representing the up contact position, are the relays that are normally following normal code.

Referring now to FIG. 4 of the drawings, there is 55 shown a traffic lever designated FL which controls the direction of traffic through the track stretch between signals 1EG and 2WG. This lever controls the pickup or release of a lever repeater relay NLPR accordingly as the lever is in its right or left position. When lever FL is in its right or R position a circuit is completed for picking up relay NLPR which extends for terminal B of the battery over contact a of the lever in its R posi-

tion and through the winding of the relay to terminal N of the battery. The pickup of relay NLPR by the lever in its R position conditions the apparatus at signal 2WG location to apply normal code to track section 2T for a train movement from left to right through the track stretch shown in the drawings. As previously set forth this is the normal condition of the system shown. The movement of lever FL from its R position to its left or L position releases relay NLPR, removes the normal code from track section 2T, and initiates a reversal of the traffic controlling system as will be described.

There is also shown in FIG. 4 track relay 2WTR, previously mentioned, and relays 2WCR, 2WTFPR, 2WHR, and a code generating relay 75CTRC. The latter relay is constantly energized by battery terminals B and N connected directly to its winding and operates its contacts at a speed of 75 operations per minute to generate what is commonly termed 75 code. Such relays are commonly called code transmitter relays and are well known in the art.

Relay 2WCR controls the application of reversal or normal code to track section 2T at signal 2WG location. As previously stated, under the normal status of the system normal code is being transmitted from signal location 2WG. To accomplish this transmission relay 2WCR is being intermittently picked up and released by a circuit which extends from terminal B of the battery over front contact *a* of code transmitter relay 75CTRC, the back point of contact *c* of relay 2WTFPR, to be described, the front point of contact *c* of relay NLPR and through the winding of the relay to terminal N of the battery. It is thus apparent that relay 2WCR under normal conditions follows the 75 code pulses of relay 75CTRC, that is, relay 2WCR is picked up when relay 75CTRC closes its front contact *a* and is released when relay 75CTRC opens its front contact *a* in its code generating cycles.

Relay 2WCR has a second operating circuit which extends from terminal B of the battery over the front point of contact *c* of relay 2WTR, the back point of contact *c* of relay NLPR and through the winding of the relay to terminal N of the battery. This circuit is employed for operation of relay 2WCR in generating reverse code as will be described later. A rectifier, reference 13, is connected across the winding of relay 2WCR at this time to slightly retard the release of the relay, in a manner well known in the art, when the release of relay 2WTR opens at the front point of its contact *c* the second operating circuit for relay 2WCR. The negative terminal N of the battery is connected to the back point of contact *c* of relay 2WTR to provide further retardation of the release of relay 2WCR when relay 2WTR closes the back point of its contact *c*.

A third circuit is provided for picking up relay 2WCR when it is desired to apply a long normal code pulse to track section 2T under conditions to be hereinafter described. This pickup circuit extends from terminal B of the battery, over front contact *c* of relay 2WTFPR, front contact *c* of relay NLPR and through the winding of relay 2WCR to terminal N of the battery.

As set forth above relay 2WCR, under the normal status of the system as shown, is being operated at a code speed of 75 pulses per minute by the coding action of contact *a* of relay 75CTRC. This operation of relay 2WCR supplies code pulses of 75 code to the rails of track section 2T by a first circuit extending from the positive terminal of track battery 2TBE over front contact *a* of relay 2WCR, the back point of contact *a* of relay 2WTR and to the rail of track section 2T designated by the conventional plus sign; and by a second circuit extending from the negative terminal of track battery 2TBE directly to the rail of track section 2T designated by the conventional minus sign. It is thus apparent that 75 code is normally being supplied to the rails of track sec-

tion 2T at signal location 2WG and flows through said rails to the intermediate signal location.

The control circuits for, and the operation of, the other apparatus at signal 2WG location will be described later when normal code is being transmitted in the opposite direction.

Referring now to FIGS. 3 and 5, the operation of the apparatus at the intermediate signal location, when the 75 code flowing through the rails of track section 2T from signal location 2WG is received at said intermediate location, will be described.

The winding of track relay 2ETR (FIG. 3) is connected to the rails of track section 2T by a first circuit which extends from the right hand side of the relay over back contact *b* of relay 2ECR, to be described, and to the rail of track section 2T designated by the conventional plus sign; and by a second circuit which extends from the left hand side of relay 2ETR directly to the rail of track section 2T designated by the conventional minus sign. Relay 2ETR is also provided with a stick circuit which extends from the positive rail through the front point of contact *a* of relay 2ETR to the winding of the relay. It is thus apparent that relay 2ETR is picked up when relay 2ECR is released and a pulse of code is received over the track rails, and is retained picked up for the duration of the pulse by the stick circuit over the front point of its contact *a*, regardless of the action of back contact *b* of relay 2ECR thereafter. Relay 2ETR is, therefore, normally following coded energy received from the rails of track section 2T.

The code following action of relay 2ETR provides pickup circuits for relays 2ETFPR and EWHR shown in FIG. 3. The pickup circuit for relay 2ETFPR extends from terminal B of the battery over back contact *d* of relay WSR, back contact *a* of relay ECCR, to be described, the front point of contact *b* of relay 2ETR, and through the winding of relay 2ETFPR to terminal N of the battery. The release time of relay 2ETFPR is sufficiently retarded by a rectifier snub 21 across the winding of the relay, that the relay will remain picked up during the normal off period of the coded track energy when relay 2ETR is released opening the front point of its contact *b*. The use of such rectifier snubs to provide retardation of release time is well known to those versed in the art. Relay EWHR has a pickup circuit which extends from terminal B of the battery over back contact *d* of relay WSR, back contact *a* of relay ECCR, the back point of contact *b* of relay 2ETR, the back point of contact *b* of relay 1WTFPR, to be described, the front point of contact *b* of relay 2ETFPR and through the winding of relay EWHR to terminal N of the battery. A capacitor-resistor unit, reference 23, is employed at this time to maintain relay EWHR in the picked up position during the on periods of the coded track pulses, that is, when the back point of contact *b* of relay 2ETR is open. This unit is connected in multiple with relay EWHR when relay 2ETFPR is energized due to the code following action of relay 2ETR, and receives a storage of energy during the closed periods of the back point of contact *b* of relay 2ETR. The circuit for charging capacitor-resistor unit 23 may be traced from battery terminal B, over back contact *d* of relay WSR, over back contact *a* of relay ECCR, the back point of contact *b* of relay 2ETR, the front point of contact *a* of relay 2ETFPR, and through the unit to battery terminal N. During the open period of the back point of contact *b* of relay 2ETR, the charge of energy stored in unit 23 is discharged through relay EWHR over the front point of contact *a* of relay 2ETFPR and the previously described pickup circuit for relay EWHR including the back point of contact *b* of relay 1WTFPR. Relay EWHR is thus maintained in its picked up position during the open period of the back point of contact *b* of relay 2ETR in its code following action. Whenever relay 2ETFPR is released, a circuit is completed to

dissipate the energy stored in unit 23 and cause immediate release of relay EWHR. This circuit extends from the left hand terminal of unit 23 over the back point of contact *a* of relay 2ETFPR to the right hand terminal of unit 23. It is well to point out at this time that relay EWHR is a slow pickup relay to protect against momentary loss of track circuit shunt by a train traversing track sections 1T or 2T.

There is shown in FIG. 5 the previously mentioned slow release relay which is employed at the intermediate signal location to determine the direction of normal code being received, and which controls the operation of my invention. This slow release relay is relay ECCR which is provided with a rectifier snub, reference 29, to obtain the slow release feature by delaying the decay of flux through the winding of the relay. As shown in FIG. 3, under the normal status of the circuits described above relay ECCR is released.

Relay 1WCR shown in FIG. 3 is the westward coding relay for track section 1T and is following 75 code at this time. The circuit for coding 1WCR at the 75 code rate extends from terminal B of the battery over the back point of contact *c* of relay 1WTFPR, front contact *a* of code transmitter relay 75CTRB, which is a relay similar to relay 75CTRC shown in FIG. 4 previously described, the front point of contact *c* of relay EWHR, back contact *c* of relay WSR, to be described, and through the winding of relay 1WCR to terminal N of the battery. Contact *a* of relay 1WCR (FIG. 3) is supplying coded energy to track section 1T at the 75 code rate in a manner similar to the manner in which contact *a* of relay 2WCR (FIG. 4), previously described supplies coded energy to track section 2T. This circuit for supplying coded energy to track section 1T extends from the positive terminal of track battery 1TBE over front contact *a* of relay 1WCR, the back point of contact *a* of code following track relay 1WTR and to the rail of track section 1T designated by the conventional plus sign. The negative terminal of track battery 1TBE is connected directly to the rail of track section 1T designated by the conventional minus sign. It is thus apparent that the pickup of relay EWHR, by its pickup circuit previously described, allows relay 1WCR to follow 75 code and apply coded energy at the 75 code rate to track section 1T.

Relay 1WTR, the code following track relay for track section 1T at the intermediate signal location, is, at this time, following reverse code being received over the rails of track section 1T from 1EG signal location during the off periods of the normal code being supplied to the rails by relay 1WCR. The circuit for supplying this reverse code to the rails of track section 1T at 1EG location will be described later, but it is desired to point out at present the reverse code following action of relay 1WTR. When relay 1WCR is released during the off period of the normal code being supplied to track section 1T, a circuit is completed for connecting relay 1WTR to the rails of the track section. This circuit extends from the plus rail of section 1T through back contact *b* of relay 1WCR and through the winding of relay 1WTR to the minus rail of section 1T. Thus, when an off period or normal code supplied to 1T occurs, relay 1WTR is connected to the rails to receive an on period of reverse code.

Relay 1WTFPR (FIG. 3) has a pickup circuit which extends from terminal B of the battery over back contact *e* of relay ESR, back contact *e* of relay 2ETFPR, the front point of contact *b* of relay 1WTR and through the winding of relay 1WTFPR to terminal N of the battery. Relay 1WTFPR is also provided with a rectifier snub 20 to snub the relay sufficiently to bridge the open periods of contact *b* of relay 1WTR during the periods when relay 1WTR is following normal code as will be herein-after described. At the present time relay 1WTFPR remains released due to its above described pickup circuit being open at back contact *e* of relay 2ETFPR. Thus

relay 1WTFPR will not pick up when relay 1WTR is following reverse code.

Referring again to FIG. 5 there is shown a relay WTPR which is picked up when relay 1WTR is following reverse code. The pickup circuit for relay WTPR extends from terminal B of the battery over front contact *c* of relay 1WTR and through the winding of relay WTPR to terminal N of the battery. Relay WTPR is provided with a capacitor-resistor unit, reference 30, across its winding to sufficiently retard the release time of the relay to bridge the relatively long open periods of front contact *c* of relay 1WTR in its reverse code following action. The use of such capacitor-resistor units to provide a relatively long release time of relays is well known in the art. Relay WTPR, therefore, remains picked up during the code following action of relay 1WTR in following reverse code, or in following normal code as will be explained later. It is thus apparent that the only time relay WTPR is released is when 1WTR is not following code such as when track section 1T is occupied by a train.

The signals 1EG, 1WG, 2EG and 2WG are shown in the drawings as being of the color-light type and the lighting circuit for signal 2EG is shown in FIG. 5. Signal 2EG is shown as having two lamps, green and red, designated by the reference characters 2EGGE and 2EGRE, respectively. The indications resulting from the illumination of the green or red lamps being illuminated individually are proceed and stop, respectively. Signal 1WG is shown in a similar manner in FIG. 5 and has lamps designated 1WGGE and 1WGRE which give the same indications as the similar lamps of signal 2EG. The colors displayed and the indications given by signals 1EG and 2WG will be described later.

Under the normal conditions of the circuits as described above a circuit is prepared for illumination of signal 2EG to display a green lamp and thus give a proceed indication. This circuit may be traced from back contact *b* of relay WTPR over back contact *d* of relay 1WTFPR, front contact *f* of relay EWHR, front contact *h* of relay 2ETFPR and through the filament of lamp 2EGGE to terminal N of the battery. This circuit is completed when terminal B of the battery, connected to the movable portion of contact *b* of relay WTPR, is supplied to the circuit over the back contact *b* of that relay. This action occurs when a train enters track section 1T and shunts the reverse code being transmitted from signal location 1EG (as will be described later) thereby stopping the reverse code following action of relay 1WTR and releasing relay WTPR. It is thus apparent that signal 2EG is normally dark but is approach lighted when a train enters track section 1T.

As previously set forth, relay 1WCR (FIG. 3) is supplying normal code to track section 1T under the normal state of the circuits as shown in the drawings. At signal 1EG location code following track relay 1ETR is following the normal code pulses being received from the rails. As is obvious, the track circuit arrangement at this location, including relay 1ETR, contacts *a* and *b* of relay 1ECR, to be described, and track battery 1TBW is identical to the track circuit arrangement of 2ETR, contacts *a* and *b* of relay 2ECR and track battery 2TBW at the intermediate signal location, and a detailed description of the arrangement is unnecessary. Therefore, for the purposes of simplification of this description it is sufficient to state that relay 1ETR is following the normal code pulses being received over the rails and a description of the supplying of reverse code to the rails at signal location 1EG will be given.

Relays 1ETFPR and 1EHR constitute the code detecting relays at signal 1EG location, similar to relays 2WTFPR and 2WHR, respectively, at signal 2WG location. Relay 1ETFPR has a pickup circuit which extends from terminal B of the battery over the front point of contact *b* of relay 1ETR and through the winding of relay 1ETFPR to terminal N of the battery. Relay

1ETFPR is provided with a rectifier snub across its winding to maintain the relay picked up during the open periods of the front point of contact *b* of relay 1ETR in its code following action. Relay 1EHR has a pickup circuit which extends from terminal B of the battery over the back point of contact *b* of relay 1ETR, front contact *b* of relay 1ETFPR and through the winding of relay 1EHR to terminal N of the battery. Relay 1EHR is provided with a capacitor-resistor unit snub, reference 6, to retain relay 1EHR picked up during the open periods of the back point of contact *b* of relay 1ETR in its code following action. Capacitor-resistor unit 6 has a charging circuit which extends from terminal B of the battery over the back point of contact *b* of relay 1ETR, the front point of contact *a* of relay 1ETFPR and through the unit to terminal N of the battery. The discharge circuit from this unit through the winding of relay 1EHR extends from the left hand terminal of the unit over the front point of contact *a* of 1ETFPR, front contact *b* of 1ETFPR and through the winding of relay 1EHR to terminal N of the battery. A circuit is provided for quickly dissipating the energy stored in unit 6 when relay 1ETFPR is released. This circuit extends from the left hand terminal of unit 6 over the back point of contact *a* of relay 1ETFPR and to the left hand terminal of the unit.

Coding relay 1ECR (FIG. 2) is supplying reverse code to track section 1T as previously stated. The circuit for operating this relay at this time extends from terminal B of the battery over the front point of contact *c* of relay 1ETR, the front point of contact *c* of relay 1ETFPR and through the winding of the relay to terminal N of the battery. Relay 1ECR is thus picked up when relay 1ETR closes its front contact *c* on each on pulse of the normal code received over track section 1T. Front contact *a* of relay 1ECR is thus closed to connect the positive terminal of track battery 1TBW to the plus rail of track section 1T, but this circuit is open at the back point of contact *a* of relay 1ETR for the duration of each on pulse of the normal code as the stick circuit for relay 1ETR over the front point of its own contact *a* maintains that relay picked up for the duration of each on pulse of normal code regardless of the opening of the pickup circuit for relay 1ETR at the back point of contact *b* of relay 1ECR. At the end of each on pulse of the normal code relay 1ETR is released, opening at the front point of contact *c* of relay 1ETR the pickup circuit for relay 1ECR. However, a snubbing circuit for relay 1ECR including a snubbing rectifier, reference 8, and terminal N of the battery connected to the back point of contact *c* of relay 1ETR, maintains relay 1ECR in a picked up position for short periods after the release of relay 1ETR during the off periods of the normal code. Reverse code is, therefore, supplied to the rails of track section 1T during the off periods of normal code, over front contact *a* of relay 1ECR and the back point of contact *a* of relay 1ETR.

Signal 1EG, as previously stated, is a color-light signal. The signal is shown as having a yellow lamp 1EGYE and a red lamp 1EGRE, and the indications given by the individual illumination of these yellow and red lamps are caution and stop, respectively. The circuit for illumination of the red lamp extends from terminal B of the battery over the back point of contact *a* of relay 1EHR and through the filament of lamp 1EGRE to terminal N of the battery. The circuit for illumination of the yellow lamp extends from terminal B of the battery over the front point of contact *a* of relay 1EHR and through the filament of lamp 1EGYE to terminal N of the battery. Under the normal condition of the apparatus shown in the drawings signal 1EG is, therefore, giving a caution indication to allow a train to proceed past the signal 1EG in an eastward direction. For purposes of simplicity the circuits shown do not provide for giving a green indication on signal 1EG but it will be obvious to those skilled

in the art that additional codes can be used to provide additional indications in the manner well known in the art, but as these additional indications are not necessary for illustration of my invention provisions therefore have not been shown.

Having thus described the operation of the part of the apparatus involved under the normal condition of the circuits illustrated, I will now describe the operation of apparatus involved when the direction of traffic through the track stretch shown is reversed to allow for a west-bound train movement by the clearing of signals 1WG and 2WG.

Referring again to FIG. 4 it will be well to first mention that signal 2WG normally gives a stop indication as traffic is normally aligned for an eastward train movement through the track stretch shown in the drawings. Similarly to signal 1EG, signal 2WG is a color-light signal and has a yellow lamp 2WGYE and a red lamp 2WGRE the individual illumination of which lamps gives caution and stop indications, respectively. The circuit for energizing lamp 2WGRE extends from terminal B of the battery over the back point of contact *a* of relay 2WHR and through the filament of lamp 2WGRE to terminal N of the battery. The circuit for energizing lamp 2WGYE extends from terminal B of the battery over the front point of contact *a* of relay 2WHR and through the filament of lamp 2WGYE to terminal N of the battery.

When it is desired to reverse the direction of traffic through the track stretch and clear signal 2WG, control lever PL in FIG. 4 is moved to its L or left position. The movement of lever L from its R position opens the pickup circuit for relay NLPR and that relay releases. The release of relay NLPR opens at the front point of its front contact *c* the previously described pickup circuit for relay 2WCR, the relay ceases to follow code and, after the expiration of the retardation of the release time of relay 2WCR provided by its snubbing circuits, relay 2WCR releases and remains in that position. The release of relay 2WCR opens at its front contact *a* the previously traced circuit for supplying coded energy to track section 2T and removes the coded energy previously supplied to that track section.

The removal of coded track energy from track section 2T causes relay 2ETR at the intermediate signal location (FIGS. 3 and 5) to cease following code and that relay releases and remains so. The steady release of relay 2ETR opens the pickup circuit for relay 2ETFPR at the front point of contact *b* of relay 2ETR and, after the effects of the rectifier snub 21 have ceased, relay 2ETFPR releases. The release of relay 2ETFPR opens at its front contact *b* the previously traced pickup circuit for relay EWHR which releases. The release of relay EWHR opens at its front contact *c* the pickup circuit for relay 1WCR and that relay ceases to follow the code action of front contact *a* of code transmitter relay 75CTRB, and relay 1WCR releases and remains in the released position. Relay 1WCR remaining in the released position removes from track section 1T the normal code pulses previously applied thereto.

The removal of coded track energy from track section 1T causes relay 1ETR (FIG. 2) to cease following code, remain released, and open at the front point of its contact *b* the pickup circuit for relay 1ETFPR which subsequently releases. The release of relay 1ETFPR opens at its front contact *b* the pickup circuit for relay 1EHR which also releases. The release of relay 1EHR transfers the energizing circuit for the lamps of signal 1EG from the yellow lamp 1EGYE to the red lamp 1EGRE and signal 1EG changes from a caution indication to a stop indication.

An additional relay 75CTRA is shown in FIG. 2. Relay 75CTRA is a code transmitter relay similar to relay 75CTRC in FIG. 4 and no further description thereof is considered necessary. The release of relay 1ETFPR as described above closes a pickup circuit for

relay 1ECR which causes relay 1ECR to follow 75 code. This circuit extends from terminal B of the battery over front contact *a* of relay 75CTRA, the back point of contact *c* of relay 1ETFPR, and through the winding of relay 1ECR to terminal N of the battery. It is thus apparent that relay 1ECR begins to follow the 75 code generated by relay 75CTRA, and applies to track circuit 1T over its front contact *a* and the back point of contact *a* of relay 1ETR normal 75 code pulses.

The previously described release of relay 2ETFPR when relay 2ETR ceased following code established the pickup circuit for relay 1WTFPR, previously described, over back contact *e* of relay 2ETFPR. Relay 1WTFPR accordingly picks up when relay 1WTR begins to follow the normal code pulses being received over track circuit 1T, and a second pickup circuit for relay EWHR is completed. This pickup circuit for relay EWHR extends from terminal B of the battery over back contact *e* of relay ESR, back contact *e* of relay 2ETFPR, the back point of contact *b* of relay 1WTR, the back point of contact *b* of relay 2ETFPR, the front point of contact *b* of relay 1WTFPR, and through the winding of relay EWHR to terminal N of the battery. A capacitor-resistor unit, reference 22, is employed at this time to maintain relay EWHR picked up when the back point of contact *b* of relay 1WTR is open. The circuit for charging this unit extends from terminal B of the battery over back contact *e* of relay ESR, back contact *e* of relay 2ETFPR the back point of contact *b* of relay 1WTR, the front point of contact *a* of relay 1WTFPR and through the unit to terminal N of the battery. The circuit for discharging the storage in the unit through the winding of relay EWHR and maintaining the relay picked up, when relay 1WTR opens the back point of its contact *b*, extends from the right hand side of the unit over the front point of contact *a* of relay 1WTFPR and thence over the pickup circuit for relay EWHR, just described. Unit 22 also has a circuit for dissipating any energy stored therein when relay 1WTFPR releases. This circuit extends from the right hand side of the unit over the back point of contact *a* of relay 1WTFPR to the left hand side of the unit.

The pickup of relay 1WTFPR also closes a circuit for pickup of relay ECCR shown in FIG. 5. This circuit extends from terminal B of the battery over the back point of contact *c* of relay 2ETR, back contact *f* of relay 2ETFPR, front contact *f* of relay 1WTFPR and through the winding of relay ECCR to terminal N of the battery. There is shown in multiple with front contact *f* of relay 1WTFPR in the pickup circuit for relay ECCR, a front contact *e* of relay WSR. The use of this contact will be brought out later in the description.

The pickup of relay ECCR indicates that any code received at the intermediate location from track section 2T will be reverse code and not normal code as will become apparent later. The pickup of relay ECCR opens at back contact *a* of that relay the previously described pickup circuit for relay 2ETFPR. Therefore, when reverse code is received from track section 2T, relay 2ETFPR will remain released and signal 2EG cannot clear for a train movement in the wrong direction.

The pickup of relays 1WTFPR and EWHR also prepares the lighting circuits for signal 1WG to give a proceed indication instead of the red indication. This signal, similar to signal 2EG, is normally dark, one of its lamps being illuminated when relay ETPR, to be described, is released. The circuit for energizing the green lamp 1WGGE of signal 1WG extends from terminal B of the battery over back contact *b* of relay ETPR, the back point of contact *g* of relay 2ETFPR, the front point of contact *e* of relay EWHR, the front point of contact *g* of relay 1WTFPR and through the filament of the lamp to terminal N of the battery. The red lamp 1WGRE of signal 1WG is energized by obvious circuits when relay ETPR is released, over back contact *b* of relay

ETPR, and the front point of contact *g* of relay 2ETFPR, or the back point of contact *e* of relay EWHR, or the back point of contact *g* of relay 1WTFPR. No detailed description of these circuits is believed necessary.

- 5 Relay ETPR is the approach lighting relay for signal 1WG and is released only when relay 2ETR is released for a period of time as when track section 2T is occupied by a train. The pickup circuit for relay ETPR extends from terminal B of the battery over the front point of contact *c* of relay 2ETR and through the winding of relay ETPR to terminal N of the battery. Relay ETPR is provided with a capacitor-resistor unit snub, reference 31, across its winding to provide the relay with a relatively long release time after the opening of its pickup circuit. This release time is sufficiently long to bridge the open period of the front point of contact *c* of relay 2ETR when that relay changes from following normal code to following reverse code, or vice versa.
- 10 When relay EWHR picks up as set forth above for a westward train movement, that is, when normal code is being received at the intermediate signal location from track section 1T, a circuit is completed for coding relay 2ECR to apply normal code to track section 2T. This circuit extends from terminal B of the battery over the back point of contact *d* of relay 2ETFPR, front contact *b* of code transmitter relay 75CTRB, the front point of contact *d* of relay EWHR, front contact *b* of relay ECCR, back contact *c* of relay ESR, to be described, and through the winding of relay 2ECR to terminal N of the battery.
- 15 It is thus apparent that relay 2ECR begins to follow the 75 code pulses produced by code transmitter relay 75CTRB, and supplies coded energy at the 75 code rate to track section 2T over front contact *a* of relay 2ECR and the back point of contact *a* of relay 2ETR.
- 20 The 75 code being supplied to track section 2T as described above, is received at signal 2WG location and relay 2WTR begins to follow the code pulses completing a pickup circuit for relay 2WTFPR. This circuit may be traced from terminal B of the battery over the front point of contact *b* of relay 2WTR and through the winding of relay 2WTFPR to terminal N of the battery. Relay 2WTFPR is provided with a rectifier snub to retard the release of relay 2WTFPR sufficiently to bridge the open periods of the front point of contact *b* of relay 2WTR in its code following action.
- 25 The pickup of relay 2WTFPR completes a pickup circuit for relay 2WHR which may be traced from terminal B of the battery over the back point of contact *b* of relay 2WTR, back contact *b* of relay NLPR, front contact *b* of relay 2WTFPR and through the winding of relay 2WHR to terminal N of the battery. A capacitor-resistor unit snub, reference 12, is provided to maintain relay 2WHR in its picked up position when the back point of contact *b* of relay 2WTR opens during its code following action. The charging circuit for this unit extends from terminal B of the battery over the back point of contact *b* of relay 2WTR, the front point of contact *a* of relay 2WTFPR and through unit 12 to terminal N of the battery. The discharge circuit from unit 12 through the winding of relay 2WHR extends from the right hand side of the unit through the front point of contact *a* of relay 2WTFPR and thence over the pickup circuit for relay 2WHR, previously described, to terminal N of the battery. A circuit for dissipating the energy stored in unit 12 when relay 2WTFPR is released extends from the right hand side of the unit through the back point of contact *a* of relay 2WTFPR to the left hand side of unit 12.
- 30

- 35 The pick up of relay 2WHR completes the energizing circuit of lamp 2WGYE of signal 2WG over the front point of contact *a* of relay 2WHR, and opens at the back point of contact *a* of relay 2WHR the energizing circuit for lamp 2WGRE of signal 2WG. Signal 2WG, therefore, now displays a yellow lamp and gives a caution indication.

The code following action of relay 2WTR starts relay 2WCR to operating to generate reverse code pulses and supplying the pulses to track section 2T during the off periods of the normal code. This circuit for operating relay 2WCR is the previously traced circuit including back contact *c* of relay NLPR and coding contact *c* of relay 2WTR. Relay 2WCR is picked up during the on period of the normal code when relay 2WTR picks up and remain up for a short period after the release of 2WTR due to the snubbing effect of rectifier 13 and the negative terminal of the battery connected to the back point of contact *c* of relay 2WTR. Therefore, after the release of relay 2WTR during the off period of the normal code, a short pulse of reverse code is applied to track section 2T over front contact *a* of relay 2WCR and the back point of contact *a* of relay 2WTR.

The above described pulses of reverse code applied to track section 2T operate relay 2ETR at the intermediate signal location and relays ETPR and ECCR remain energized due to the intermittent closing of the front and back points of contact *c* of relay 2ETR. Relay 2ETFPR cannot pick up because its pickup circuit is open at back contact *a* of relay ECCR, as previously mentioned, and relay 1WCR cannot operate to supply code to track section 1T because its pickup circuits are open at the back point of contact *c* of relay IWTFPR and the front point of contact *c* of relay 2ETFPR. No reverse code is supplied beyond the intermediate signal location, therefore.

I will now described the operation of the circuit and apparatus arrangement when the direction of traffic is to be changed to its previously described normal direction, and will thereafter describe the operation of the arrangement when trains move through the track stretch.

To change the direction of traffic through the track stretch in the eastward direction or the direction from left to right again, lever FL is moved from the L position to the R position. Relay NLPR is picked up over its previously described pickup circuit over contact *a* of lever FL. The pickup of relay NLPR prepares circuits for applying a pulse of normal code to track section 2T at signal 2WG location, which pulse is somewhat longer than the normal pulses of normal code. The first of these circuits charges a capacitor-resistor unit, reference 11, on the next pulse of normal code received from track section 2T when relay 2WTR is picked up. This circuit extends from terminal B of the battery over the front point of contact *b* of relay 2WTR, the front point of contact *a* of relay NLPR and through the capacitor-resistor unit 11 to terminal N of the battery. The second circuit picks up relay 2WCR and extends from terminal B of the battery over the front point of contact *c* of relay 2WTFPR, the front point of contact *c* of relay NLPR and through the winding of relay 2WCR to terminal N of the battery. Relay 2WCR is thus picked up to apply a pulse of code to track section 2T over front contact *a* of relay 2WCR and back contact *a* of relay 2WTR, when relay 2WTR releases upon the termination of the previously mentioned pulse of code supplied to relay 2WTR from track section 2T. Relay 2WTR opens its stick circuit over the front point of its own front contact *a* and can receive no more pulses of code from track section 2T until back contact *b* of relay 2WCR is closed. However, the opening of the front point of contact *b* of relay 2WTR permits the capacitor-resistor unit 11 to discharge its storage through the winding of relay 2WTFPR and this relay remains picked up for a relatively long period of time although its pickup circuit is open at the front point of contact *b* of relay 2WTR. Relay 2WCR thus remains picked up until relay 2WTFPR releases and opens the front point of its contact *c*. It is, therefore, apparent that a relatively long pulse of code is applied to track section 2T over front contact *a* of relay 2WCR. It is well to point out at this time that unit 11 has a circuit for dissipating any storage contained

therein, when relay NLPR is released. This circuit extends from the right hand side of the unit over the back point of contact *a* of relay NLPR to the left hand side of the unit. It should also be pointed out that when relay 5 NLPR is released unit 11 can have no effect on relay 2WTFPR.

When the snubbing effect of the storage in capacitor-resistor unit 11 being supplied to the winding of relay 2WTFPR wears off, relay 2WTFPR releases and the 10 winding of relay 2WCR is connected to the coding contact *a* of relay 75CTRC, relay 2WCR begins to follow 75 code, and supplying normal code pulses to track section 2T. The pickup of relay NLPR as mentioned above, also 15 opens at its back contact *b* the pickup circuit for relay 2WHR which releases changing the energizing circuits for the lamps of signal 2WG from the yellow lamp 2WGYE to the red lamp 2WGRE. Signal 2WG thus gives a stop indication.

The long pulse of normal code supplied to track section 2T as set forth above, "overrides" the pulses of normal code being supplied to track section 2T at the intermediate signal location as relay 2ETR, when relay 2ECR releases during an off pulse of code, is picked up by the long pulse of normal code and remains up for the duration of the long pulse. Relay 2ECR, therefore, can no longer supply normal code to track section 2T as the circuit for so supplying the code is open at the back point of contact *a* of relay 2ETR.

30 Relay 2ETR is held up for a sufficient period of time by the long pulse of code received, that the effect of the rectifier snub 29 across the winding of relay ECCR disappears and relay ECCR releases. The release of relay ECCR closes the pickup circuit for relay 2ETFPR over back contact *a* of relay ECCR and relay 2ETFPR is picked up. The pickup of relay 2ETFPR opens at the back point of its contact *b* the pickup circuit for relay EWHR which releases. The release of relay ECCR also opens at its front contact *b* the pickup circuit for relay 2ECR and that relay ceases to follow the code generated by contact *b* of relay 75CTRB. Thus normal code is no longer applied to track section 2T by the operation of relay 2ECR.

The pickup of relay 2ETFPR and the release of relay 45 EWHR picks up relay 1WCR to supply a long pulse of normal code to track section 1T when relay 1WTR is released during the next off pulse of code received from track section 1T. This circuit for picking up relay 1WCR extends from terminal B of the battery over the front point of contact *c* of relay 2ETFPR, the back point 50 of contact *a* of relay ESR, the back point of contact *c* of relay EWHR, back contact *c* of relay WSR and through the winding of relay 1WCR to terminal N of the battery. Thus relay 1WCR is picked up and supplies a pulse of code to track section 1T over its front contact *a* and the back point of contact *a* of relay 1WTR when relay 1WTR releases during the off pulse of the code received from track section 1T. Relay 1WTR cannot pick up on the next on pulse of code from track section 55 1T since relay 1WCR remains picked up, and the pickup circuit for relay 1WTR is open at back contact *b* of relay 1WCR. When relay 2ETFPR picked up as described above, the pickup circuit for relay 1WTFPR was opened at back contact *e* of relay 2ETFPR. However, due to the effect of the rectifier snub 20 across the winding of relay 1WTFPR, the relay does not immediately release. Accordingly, relay 1WCR remains picked up until relay 1WTFPR releases to establish the pickup circuit for relay EWHR over the back point of contact *b* of relay 1WTFPR and the front point of contact *b* of relay 2ETFPR. Relay EWHR is again picked up and the coding circuit for relay 1WCR is again completed 60 over the front point of contact *c* of relay EWHR. Relay 1WCR accordingly follows the 75 code pulses supplied by contact *a* of relay 75CTRB, and supplies pulses 65 70 75

of 75 code to track section 1T over its front contact *a*. The pickup of relay 2ETFPR as described above opened at the back point of its contact *g* the circuit for lamp 1WGGE of signal 1WG and prepares the circuit for lamp 1WGRE of that signal over the front point of its contact *g*. The transfer of contact *h* of relay 2ETFPR from its back point to its front point changes a circuit for signal 2EG from its red lamp 2EGRE to its green lamp 2EGGE. The release of relay 1WTFPR and pickup of relay EWHR finishes the preparation of the circuit for lamp 2EGGE over the back point of contact *d* of relay 1WTFPR and the front point of contact *f* of relay EWHR. The operation of these relays also opens the circuit for lamp 2EGRE at the front point of contact *d* of relay 1WTFPR and back point of contact *f* of relay EWHR.

The long pulse of code supplied to track section 1T at the intermediate signal location "overrides" the code being supplied to track section 1T at signal 1EG location (FIG. 2) and track relay 1ETR picks up. The pickup of relay 1ETR disconnects contact *a* of relay 1ECR from the rails to prevent transmission of further normal code pulses from signal 1EG location. The pickup of relay 1ETR also picks up relay 1ETFPR over the circuit including the front point of contact *b* of relay 1ETR. The pickup of relay 1ETFPR opens at the back point of its contact *c* the coding circuit over front contact *a* of relay 75CTRA, and closes at the front point of its contact *c* the reverse coding circuit over the front and back points of contact *c* of relay 1ETR. When relay 1ETR releases at the end of the long normal code pulse and begins to follow the normal code pulses being received from track section 1T, relay 1EHR is picked up to change the indication given by signal 1EG from stop to caution. Relay 1ECR also begins to supply reverse code pulses to track section 1T over its front contact *a* and the back point of contact *a* of relay 1ETR. The arrangement shown in the drawings is now again in its normal condition previously described.

I will now assume that the circuits are in their normal condition as shown, with signal 1EG cleared for an eastward train movement through the track stretch. I will also assume that a train accepts signal 1EG and enters track section 1T.

The wheels and axles of the train entering track section 1T shunts both the normal and reverse codes flowing over the rails of track section 1T. At signal 1EG location relay 1ETR is released, releasing in turn relay 1ETFPR which releases relay 1EHR. Signal 1EG is thus controlled to give its stop indication to any following train desiring to enter track section 1T. The shunting of the reverse code by the train releases relay 1WTR at the intermediate signal location and subsequently relay WTPR releases after the effect of its snub 30 is gone. The release of WTPR completes the energizing circuit for lamp 2EGGE of signal 2EG over the back contact *b* of relay WTPR and the signal gives its proceed indication for the train to enter track section 2T when it arrives at signal 2EG.

The release of relay WTPR also completes a circuit for picking up directional stick relay ESR shown in FIG. 3. This circuit extends from terminal B of the battery over the front point of contact *d* of relay 2ETFPR, the back point of contact *a* of relay WTPR, front contact *a* of relay EWHR, the front point of contact *a* of relay ETPR and through the winding of relay ESR to terminal N of the battery. When the train accepts signal 2EG and releases relay 2ETR by shunting the normal code flowing over track section 2T, relays 2ETFPR and EWHR are also released in turn. The release of relay EWHR opens the just described pickup circuit for relay ESR but a stick circuit for relay ESR is closed to maintain relay ESR picked up. This circuit extends from terminal B of the battery over back contact *b* of relay EWHR, the back point of contact *b* of relay WSR,

the front point of contact *b* of relay ESR and through the winding of relay ESR to terminal N of the battery. Relay ESR is provided with a resistor snub, reference 25, across its winding to make the relay sufficiently slow release to bridge the transfer time from the opening of the pickup circuit for relay ESR at front contact *a* of relay EWHR, to the closing of the stick circuit for relay ESR at the back contact *b* of relay EWHR.

The pickup of relay ESR establishes a circuit for coding 1WCR at the 75 code rate and supplying normal code to track section 1T. This circuit extends from terminal B of the battery over the back point of contact *c* of relay 1WTFPR, front contact *a* of relay 75CTRB, the front point of contact *a* of relay ESR, the back point of contact *c* of relay EWHR, back contact *c* of relay WSR and through the winding of relay 1WCR to terminal N of the battery. It is thus apparent that relay 1WCR again operates to supply 75 code to track section 1T when relay ESR is picked up.

It is desired to point out that, when the train entered track section 1T and released relay 1ETFPR as described above, relay 1ECR at signal 1EG location is operated at the 75 code rate by the circuit including the back point of contact *c* of relay 1ETFPR. The operation of relay 1ECR applies normal code to track section 1T over front contact *a* of relay 1ECR and the back point of contact *a* of relay 1ETR. This code is shunted by the wheels and axles of the train occupying section 1T but follows the train through the section. When the train vacates track section 1T and is wholly within track section 2T, relay 1WTR can follow the normal code pulses received but relay 1WTFPR cannot pick up due to its pickup circuit being open at back contact *e* of relay ESR. Therefore, relay EWHR cannot pick up and clear the improper signal 1WG.

As described above relay 1WCR is also operating to supply normal code to track section 1T at this time. For a short period, therefore, the two normal codes may be supplied to track section 1T simultaneously, but the normal code being supplied at the intermediate signal location will eventually pick up relay 1ETR at signal 1EG location. The pick up of relay 1ETR will in turn pick up relay 1ETFPR, remove the normal code supplied to track section 1T at signal 1EG location, and condition the apparatus at that location to supply reverse code pulses to track section 1T. The opposite effect cannot occur as relay 1WTFPR at the intermediate signal location cannot be picked up since its pickup circuit is open at back contact *e* of relay ESR. The receipt of the normal code at signal 1EG location and pickup of relay 1ETFPR, picks up in turn relay 1EHR and signal 1EG gives a caution indication for a train movement into track section 1T for any second train that may be following the first train described above. This second train could not, of course, proceed past signal 2EG until

the first train has vacated track section 2T, as signal 2EG was operated to give its stop indication when the first train entered track section 2T releasing relays 2ETFPR and in turn relay EWHR. The circuit for energizing the green lamp 2EGGE of signal 2EG is first opened at the front point of contact *h* of relay 2ETFPR and then at the front point of contact *f* of relay EWHR. The circuit for energizing the red lamp 2EGRE of signal 2EG is first closed at the back point of contact *h* of relay 2ETFPR and then at the back point of contact *f* of relay EWHR.

When the first train vacates track section 1T, relay WTPR is again picked up by the reverse code following operation of track relay 1WTR and the intermittent closing of front contact *c* of that track relay. The energizing circuit for the red lamp of signal 2EG is, therefore, opened at back contact *b* of relay WTPR.

The back contact *c* of relay ESR in the pickup circuit for relay 2ECR, insures that relay 2ECR cannot be operated to supply code to track section 2T so long as the directional stick relay is picked up.

When the train described vacates track section 2T, the normal code being fed to rails of track section 2T at signal 2WG location is no longer shunted and is received at the intermediate signal location. Relay 2ETR follows the normal code pulses, relay 2ETFPR picks up, and relay EWHR also picks up to again establish the normal condition of the circuits. The pickup of relay EWHR opens at its back contact *b* the stick circuit for relay ESR over the front point of its own contact *b* and relay ESR releases. The pick-up of relay EWHR also changes the coding circuit for relay 1WCR from the circuit over the back point of contact *c* of relay EWHR and the front point of contact *a* of relay ESR, to the circuit over the front point of contact *c* of relay EWHR. The apparatus is thus now returned to its normal condition.

I will now assume that traffic is aligned for a westward train movement through the track stretch, lever FL having been moved to its L position and signals 1WG and 2WG having been cleared, as previously described.

The acceptance of signal 2WG by the westbound train and the train's entrance into track section 2T shunts the normal code being received over track section 2T from the intermediate signal location and relay 2WTFPR and, in turn, relay 2WHR are released. Signal 2WG is operated to give its stop indication to any train that may be following the first train. The reverse code being supplied to track section 2T at signal 2WG location is also shunted by the wheels and axles of the train and relay 2ETR ceases to follow the reverse code pulses, and is released, in turn releasing relay ETPR. Signal 1WG is approach lighted over the back contact *b* of relay ETPR to energize signal lamp 1WGGE of signal 1WG and give the proceed indication of the signal.

The release of relay ETPR also picks up directional stick relay WSR by a circuit which extends from terminal B of the battery over the front point of contact *c* of relay 1WTFPR, the back point of contact *a* of relay ETPR, front contact *a* of relay EWHR, the front point of contact *a* of relay WTPR and through the winding of relay WSR to terminal N of the battery. When the train enters track section 1T and shunts the normal code being received at the intermediate signal location, relay 1WTR ceases to follow code, relay 1WTFPR releases, in turn, releasing relay EWHR. The release of relay EWHR establishes a stick circuit for relay WSR. This circuit extends from terminal B of the battery over back contact *b* of relay EWHR, the back point of contact *b* of relay ESR, the front point of contact *b* of relay WSR, and through the winding of relay WSR to terminal N of the battery. Relay WSR is thus maintained picked up so long as the westbound train occupies track section 1T. Relay WSR, similar to relay ESR, is provided with a resistor snub, reference 24, across its winding to maintain relay WSR picked up during the transfer from its pickup circuit over front contact *a* of relay EWHR to its stick circuit over back contact *b* of relay EWHR and the front point of its own contact *b*.

When the westbound train first enters track section 1T, thereby releasing relay 1WTFPR as described above, the previously described pickup circuit for relay ECCR is opened at front contact *f* of relay 1WTFPR. However, the multiple circuit for relay ECCR over front contact *e* of relay WSR having been previously closed when relay WSR picked up, relay ECCR remains in its picked up condition. Therefore, any code pulses received from track section 2T, when the train has vacated that track section and is wholly within track section 1T, cannot operate to pickup relay 2ETFPR as its pickup circuit is open at back contact *a* of relay ECCR. Signal 2EG cannot, therefore, be cleared to give an improper indication.

The pickup of relay WSR also prepares a circuit for operating relay 2ECR to supply normal code pulses to track section 2T. This circuit extends from terminal B

of the battery over the back point of contact *d* of relay 2ETFPR, front contact *b* of relay 75CTR, front contact *a* of relay WSR, the back point of contact *d* of relay EWHR (assuming the westbound train has entered track section 1T), front contact *b* of relay ECCR, back contact *c* of relay ESR, and through the winding of relay 2ECR to terminal N of the battery. When the train has vacated track section 2T, therefore, the normal code pulses being supplied to track section 2T will again be received at signal 2WG location to clear that signal for any train that may be following the first westbound train.

A back contact *c* of relay WSR is employed in the pickup circuit for relay 1WCR to insure that that relay cannot be operated to supply code to track section 1T so long as relay WSR is picked up.

It should be pointed out that as long as relay NLPR at signal 2WG location remains released no normal code pulses are supplied to track section 2T in the rear of the westbound train traversing track section 2T, as the operating circuit for relay 2WCR to supply normal code pulses is open at the front point of contact *c* of relay NLPR. Therefore, the normal code pulses supplied to track section 2T at the intermediate signal location will be received at signal 2WG, when the train vacates section 2T, with no interference from normal code pulses being supplied in the other direction. However, if lever FL is returned to its R position, when the train is in section 2T, thereby picking up relay NLPR, normal code pulses are supplied to the rails of track section 2T in the rear of the train. When the train vacates track section 2T these code pulses may operate relay 2ETR but relay 2ETFPR cannot pick up as its pickup circuit is open at back contact *a* of relay ECCR. The normal code pulses being supplied to track section 2T at the intermediate signal location will eventually pick up relay 2WTR at signal 2WG location. The pick up of relay 2WTR will pick up relay 2WTFPR and complete the pickup circuit for relay 2WCR over the front point of contact *c* of relay 2WTFPR and the front point of contact *c* of relay NLPR. The release of relay 2WTR, during the next off period of the normal code received from track section 2T, does not energize relay 2WHR as its pickup circuit is open at back contact *b* of relay NLPR. Signal 2WHR is thus controlled to give its stop indication when relay NLPR is picked up. The release of relay 2WTR closes at the back point of its contact *a* the previously described circuit including front contact *a* of relay 2WCR for supplying the long pulse of normal code to track section 2T. As long as relay 2WCR remains picked up the circuit from the track rails to relay 2WTR is open at back contact *b* of relay 2WCR. Relay 2WTFPR remains picked up, after the opening of the front point of contact *b* of relay 2WTR, by the previously described circuit from the right hand side of capacitor-resistor unit 11 over the front point of contact *a* of relay NLPR and through the winding of relay 2WTFPR to terminal N of the battery. Maintaining relay 2WTFPR thus picked up for a relatively long period, maintains relay 2WCR picked up to supply the aforesaid long pulse of normal code to track section 2T.

The long pulse of normal code supplied to track section 2T being received at the intermediate signal location picks up relay 2ETR for the duration of the pulse. The pick up of relay 2ETR opens at the back point of its contact *c* the pickup circuit for relay ECCR which releases after the effects of its rectifier snub 29 have worn away. The duration of the long pulse is greater than the delayed release time of relay ECCR provided by the rectifier snub. The release of relay ECCR closes at the back contact *a* of relay ECCR the pickup circuit for relay 2ETFPR but the relay remains released as its pickup circuit remains open at back contact *d* of relay WSR. At signal 2WG location, when the delayed release effect of unit 11 have disappeared, relay 2WTFPR will release closing the back point of its contact *c* and completing the coding circuit for relay 2WCR. Relay 2WCR

of 75 code to track section 1T over its front contact *a*. The pickup of relay 2ETFPR as described above opened at the back point of its contact *g* the circuit for lamp 1WGGE of signal 1WG and prepares the circuit for lamp 1WGRE of that signal over the front point of its contact *g*. The transfer of contact *h* of relay 2ETFPR from its back point to its front point changes a circuit for signal 2EG from its red lamp 2EGRE to its green lamp 2EGGE. The release of relay 1WTFPR and pickup of relay EWHR finishes the preparation of the circuit for lamp 2EGGE over the back point of contact *d* of relay 1WTFPR and the front point of contact *f* of relay EWHR. The operation of these relays also opens the circuit for lamp 2EGRE at the front point of contact *d* of relay 1WTFPR and back point of contact *f* of relay EWHR.

The long pulse of code supplied to track section 1T at the intermediate signal location "overrides" the code being supplied to track section 1T at signal 1EG location (FIG. 2) and track relay 1ETR picks up. The pickup of relay 1ETR disconnects contact *a* of relay 1ECR from the rails to prevent transmission of further normal code pulses from signal 1EG location. The pickup of relay 1ETR also picks up relay 1ETFPR over the circuit including the front point of contact *b* of relay 1ETR. The pickup of relay 1ETFPR opens at the back point of its contact *c* the coding circuit over front contact *a* of relay 75CTRA, and closes at the front point of its contact *c* the reverse coding circuit over the front and back points of contact *c* of relay 1ETR. When relay 1ETR releases at the end of the long normal code pulse and begins to follow the normal code pulses being received from track section 1T, relay 1EHR is picked up to change the indication given by signal 1EG from stop to caution. Relay 1ECR also begins to supply reverse code pulses to track section 1T over its front contact *a* and the back point of contact *a* of relay 1ETR. The arrangement shown in the drawings is now again in its normal condition previously described.

I will now assume that the circuits are in their normal condition as shown, with signal 1EG cleared for an eastward train movement through the track stretch. I will also assume that a train accepts signal 1EG and enters track section 1T.

The wheels and axles of the train entering track section 1T shunts both the normal and reverse codes flowing over the rails of track section 1T. At signal 1EG location relay 1ETR is released, releasing in turn relay 1ETFPR which releases relay 1EHR. Signal 1EG is thus controlled to give its stop indication to any following train desiring to enter track section 1T. The shunting of the reverse code by the train releases relay 1WTR at the intermediate signal location and subsequently relay WTPR releases after the effect of its snub 30 is gone. The release of WTPR completes the energizing circuit for lamp 2EGGE of signal 2EG over the back contact *b* of relay WTPR and the signal gives its proceed indication for the train to enter track section 2T when it arrives at signal 2EG.

The release of relay WTPR also completes a circuit for picking up directional stick relay ESR shown in FIG. 3. This circuit extends from terminal B of the battery over the front point of contact *d* of relay 2ETFPR, the back point of contact *a* of relay WTPR, front contact *a* of relay EWHR, the front point of contact *a* of relay 1ETPR and through the winding of relay ESR to terminal N of the battery. When the train accepts signal 2EG and releases relay 1ETR by shunting the normal code flowing over track section 2T, relays 2ETFPR and EWHR are also released in turn. The release of relay EWHR opens the just described pickup circuit for relay ESR but a stick circuit for relay ESR is closed to maintain relay ESR picked up. This circuit extends from terminal B of the battery over back contact *b* of relay EWHR, the back point of contact *b* of relay WSR, 75

the front point of contact *b* of relay ESR and through the winding of relay ESR to terminal N of the battery. Relay ESR is provided with a resistor snub, reference 25, across its winding to make the relay sufficiently slow release to bridge the transfer time from the opening of the pickup circuit for relay ESR at front contact *a* of relay EWHR, to the closing of the stick circuit for relay ESR at the back contact *b* of relay EWHR.

The pickup of relay ESR establishes a circuit for coding 1WCR at the 75 code rate and supplying normal code to track section 1T. This circuit extends from terminal B of the battery over the back point of contact *c* of relay 1WTFPR, front contact *a* of relay 75CTRB, the front point of contact *a* of relay ESR, the back point of contact *c* of relay EWHR, back contact *c* of relay WSR and through the winding of relay 1WCR to terminal N of the battery. It is thus apparent that relay 1WCR again operates to supply 75 code to track section 1T when relay ESR is picked up.

It is desired to point out that, when the train entered track section 1T and released relay 1ETFPR as described above, relay 1ECR at signal 1EG location is operated at the 75 code rate by the circuit including the back point of contact *c* of relay 1ETFPR. The operation of relay 1ECR applies normal code to track section 1T over front contact *a* of relay 1ECR and the back point of contact *a* of relay 1ETR. This code is shunted by the wheels and axles of the train occupying section 1T but follows the train through the section. When the train vacates track section 1T and is wholly within track section 2T, relay 1WTR can follow the normal code pulses received but relay 1WTFPR cannot pick up due to its pickup circuit being open at back contact *e* of relay ESR. Therefore, relay EWHR cannot pick up and clear the improper signal 1WG. As described above relay 1WCR is also operating to supply normal code to track section 1T at this time. For a short period, therefore, the two normal codes may be supplied to track section 1T simultaneously, but the normal code being supplied at the intermediate signal location will eventually pick up relay 1ETR at signal 1EG location. The pick up of relay 1ETR will in turn pick up relay 1ETFPR, remove the normal code supplied to track section 1T at signal 1EG location, and condition the apparatus at that location to supply reverse code pulses to track section 1T. The opposite effect cannot occur as relay 1WTFPR at the intermediate signal location cannot be picked up since its pickup circuit is open at back contact *e* of relay ESR. The receipt of the normal code at signal 1EG location and pickup of relay 1ETFPR, picks up in turn relay 1EHR and signal 1EG gives a caution indication for a train movement into track section 1T for any second train that may be following the first train described above. This second train could not, of course, proceed past signal 2EG until the first train has vacated track section 2T, as signal 2EG was operated to give its stop indication when the first train entered track section 2T releasing relays 2ETFPR and in turn relay EWHR. The circuit for energizing the green lamp 2EGGE of signal 2EG is first opened at the front point of contact *h* of relay 2ETFPR and then at the front point of contact *f* of relay EWHR. The circuit for energizing the red lamp 2EGRE of signal 2EG is first closed at the back point of contact *h* of relay 2ETFPR and then at the back point of contact *f* of relay EWHR. When the first train vacates track section 1T, relay WTPR is again picked up by the reverse code following operation of track relay 1WTR and the intermittent closing of front contact *c* of that track relay. The energizing circuit for the red lamp of signal 2EG is, therefore, opened at back contact *b* of relay WTPR.

The back contact *c* of relay ESR in the pickup circuit for relay 2ECR, insures that relay 2ECR cannot be operated to supply code to track section 2T so long as the directional stick relay is picked up.

When the train described vacates track section 2T, the normal code being fed to rails of track section 2T at signal 2WG location is no longer shunted and is received at the intermediate signal location. Relay 2ETR follows the normal code pulses, relay 2ETFPR picks up, and relay EWHR also picks up to again establish the normal condition of the circuits. The pickup of relay EWHR opens at its back contact *b* the stick circuit for relay ESR over the front point of its own contact *b* and relay ESR releases. The pick-up of relay EWHR also changes the coding circuit for relay 1WCR from the circuit over the back point of contact *c* of relay EWHR and the front point of contact *a* of relay ESR, to the circuit over the front point of contact *c* of relay EWHR. The apparatus is thus now returned to its normal condition.

I will now assume that traffic is aligned for a westward train movement through the track stretch, lever FL having been moved to its L position and signals 1WG and 2WG having been cleared, as previously described.

The acceptance of signal 2WG by the westbound train and the train's entrance into track section 2T shunts the normal code being received over track section 2T from the intermediate signal location and relay 2WTFPR and, in turn, relay 2WHR are released. Signal 2WG is operated to give its stop indication to any train that may be following the first train. The reverse code being supplied to track section 2T at signal 2WG location is also shunted by the wheels and axles of the train and relay 2ETR ceases to follow the reverse code pulses, and is released, in turn releasing relay ETPR. Signal 1WG is approach lighted over the back contact *b* of relay ETPR to energize signal lamp 1WGGE of signal 1WG and give the proceed indication of the signal.

The release of relay ETPR also picks up directional stick relay WSR by a circuit which extends from terminal B of the battery over the front point of contact *c* of relay 1WTFPR, the back point of contact *a* of relay ETPR, front contact *a* of relay EWHR, the front point of contact *a* of relay WTPR and through the winding of relay WSR to terminal N of the battery. When the train enters track section 1T and shunts the normal code being received at the intermediate signal location, relay 1WTR ceases to follow code, relay 1WTFPR releases, in turn, releasing relay EWHR. The release of relay EWHR establishes a stick circuit for relay WSR. This circuit extends from terminal B of the battery over back contact *b* of relay EWHR, the back point of contact *b* of relay ESR, the front point of contact *b* of relay WSR, and through the winding of relay WSR to terminal N of the battery. Relay WSR is thus maintained picked up so long as the westbound train occupies track section 1T. Relay WSR, similar to relay ESR, is provided with a resistor snub, reference 24, across its winding to maintain relay WSR picked up during the transfer from its pickup circuit over front contact *a* of relay EWHR to its stick circuit over back contact *b* of relay EWHR and the front point of its own contact *b*.

When the westbound train first enters track section 1T, thereby releasing relay 1WTFPR as described above, the previously described pickup circuit for relay ECCR is opened at front contact *f* of relay 1WTFPR. However, the multiple circuit for relay ECCR over front contact *e* of relay WSR having been previously closed when relay WSR picked up, relay ECCR remains in its picked up condition. Therefore, any code pulses received from track section 2T, when the train has vacated that track section and is wholly within track section 1T, cannot operate to pickup relay 2ETFPR as its pickup circuit is open at back contact *a* of relay ECCR. Signal 2EG cannot, therefore, be cleared to give an improper indication.

The pickup of relay WSR also prepares a circuit for operating relay 2ECR to supply normal code pulses to track section 2T. This circuit extends from terminal B

of the battery over the back point of contact *d* of relay 2ETFPR, front contact *b* of relay 75CTR, front contact *a* of relay WSR, the back point of contact *d* of relay EWHR (assuming the westbound train has entered track section 1T), front contact *b* of relay ECCR, back contact *c* of relay ESR, and through the winding of relay 2ECR to terminal N of the battery. When the train has vacated track section 2T, therefore, the normal code pulses being supplied to track section 2T will again be received at signal 2WG location to clear that signal for any train that may be following the first westbound train.

A back contact *c* of relay WSR is employed in the pickup circuit for relay 1WCR to insure that that relay cannot be operated to supply code to track section 1T so long as relay WSR is picked up.

It should be pointed out that as long as relay NLPR at signal 2WG location remains released no normal code pulses are supplied to track section 2T in the rear of the westbound train traversing track section 2T, as the operating circuit for relay 2WCR to supply normal code pulses

is open at the front point of contact *c* of relay NLPR. Therefore, the normal code pulses supplied to track section 2T at the intermediate signal location will be received at signal 2WG, when the train vacates section 2T, with no interference from normal code pulses being supplied in the other direction. However, if lever FL is returned to its R position, when the train is in section 2T, thereby picking up relay NLPR, normal code pulses are supplied to the rails of track section 2T in the rear of the train. When the train vacates track section 2T these code pulses may operate relay 2ETR but relay 2ETFPR cannot pick up as its pickup circuit is open at back contact *a* of relay ECCR. The normal code pulses being supplied to track section 2T at the intermediate signal location will eventually pick up relay 2WTR at signal 2WG location. The pick up of relay 2WTR will pick up relay 2WTFPR and complete the pickup circuit for relay 2WCR over the front point of contact *c* of relay 2WTFPR and the front point of contact *c* of relay NLPR. The release of relay 2WTR, during the next off period of the normal code received from track section 2T, does not energize relay 2WHR as its pickup circuit is open at back contact *b* of relay NLPR. Signal 2WHR is thus controlled to give its stop indication when relay NLPR is picked up. The release of relay 2WTR closes at the back point of its contact *a* the previously described circuit including front contact *a* of relay 2WCR for supplying the long pulse of normal code to track section 2T. As long as relay 2WCR remains picked up the circuit from the track rails to relay 2WTR is open at back contact *b* of relay 2WCR. Relay 2WTFPR remains picked up, after the opening of the front point of contact *b* of relay 2WTR, by the previously described circuit from the right hand side of capacitor-resistor unit 11 over the front point of contact *a* of relay NLPR and through the winding of relay 2WTFPR to terminal N of the battery. Maintaining relay 2WTFPR thus picked up for a relatively long period, maintains relay 2WCR picked up to supply the aforesaid long pulse of normal code to track section 2T.

The long pulse of normal code supplied to track section 2T being received at the intermediate signal location picks up relay 2ETR for the duration of the pulse. The pick up of relay 2ETR opens at the back point of its contact *c* the pickup circuit for relay ECCR which releases after the effects of its rectifier snub 29 have worn away. The duration of the long pulse is greater than the delayed release time of relay ECCR provided by the rectifier snub. The release of relay ECCR closes at the back contact *a* of relay ECCR the pickup circuit for relay 2ETFPR but the relay remains released as its pickup circuit remains open at back contact *d* of relay WSR. At signal 2WG location, when the delayed release effect of unit 11 have disappeared, relay 2WTFPR will release closing the back point of its contact *c* and completing the coding circuit for relay 2WCR. Relay 2WCR

follows the 75 code pulses of relay 75CTRC and supplies normal code to track section 2T. Relay 2ETR at the intermediate signal location follows the normal code pulses but relay 2ETFPR remains released as relay WSR is still picked up. The release of relay ECCR opened at its front contact *b* the coding circuit for relay 2ECR and that relay ceases to follow 75 code and ceases to supply normal code to track section 2T.

I will now first assume that the westbound train traverses track section 1T and vacates that section with lever FL remaining in its L position. When the train vacates track section 1T, the normal code pulses being supplied to track section 1T by the code following action of relay 1ECR are again received at the intermediate signal location and relay 1WTR will again follow normal code. Relay 1WTFPR will be picked up over its pickup circuit including back contact *e* of relay 2ETFPR. The pick up of relay 1WTFPR will complete the pickup circuit for relay EWHR including the back point of contact *b* of relay 2ETFPR and the front point of contact *b* of relay 1WTFPR. Relay EWHR will pick up opening at its back contact *b* the stick circuit for relay WSR which will also release opening at its front contact *e* the multiple pickup circuit for relay ECCR. However, the circuit for relay ECCR over front contact *f* of relay 1WTFPR, having been previously closed, relay ECCR remains picked up. The pick up of relay EWHR, as described above, also opened the coding circuit for relay 2ECR over the back point of contact *d* of relay EWHR and front contact *a* of relay WSR, but closed at the front point of its contact *d* the multiple coding circuit for relay 2ECR. Relay 2ECR, therefore, continues to operate and supply normal code to track section 2T. The apparatus at signal 2WG location also continues to supply reverse code to track section 2T.

I will now assume that when the westbound train vacates track section 1T, lever NLPR had previously been returned to its right hand or R position. The circuits are, therefore, operating in the manner previously described for this condition. When the train vacates track section 1T, the normal code being supplied to track section 1T at signal 1EG location is no longer shunted and is received at the intermediate signal location. Relay 1WTR follows the code, relay 1WTFPR picks up and consequently relay EWHR picks up. The pickup of relay EWHR opens at its back contact *b* the stick circuit for relay WSR which releases. The release of relay WSR closes at its back contact *d* the pickup circuit for relay 2ETFPR which picks up, opening at its back contact *e* the pickup circuit for relay 1WTFPR, and at the back point of its contact *b* the pickup circuit for relay EWHR. Relay 1WTFPR releases and the pickup circuit for relay EWHR over the front point of contact *b* of relay 2ETFPR and the back point of contact *b* of relay 1WTFPR, is closed. Relay EWHR again picks up and signal 2EG is cleared for an eastbound move.

The previously described pickup of relay EWHR and consequential release of relay WSR prepared the coding circuit for relay 1WCR. However this circuit remained open at the front contact *c* of relay 1WTFPR. When relay 2ETFPR opens its back contact *e* as described and releases relays 1WTFPR and EWHR but subsequently again picks up relay EWHR over the front point of contact *b* of relay 2ETFPR, the coding circuit for relay 1WCR is again completed. Relay 1WCR supplies over the circuit including its front contact *a* normal code to track section 1T simultaneously with the normal code being supplied to track section 1T at signal 1EG location. However, relay 1WTFPR at the intermediate signal location is prevented from picking up by the open back contact *e* of relay 2ETFPR. There is nothing at signal 1EG location to prevent relay 1ETR from picking up when relay 1ETR is picked up by a pulse of normal code. Eventually, therefore, relay 1ETR will receive a pulse of normal code, relay 1ETFPR will pick up and the normal code being supplied to track section

1T by relay 1ECR will be removed. Relay 1ECR will now operate to supply reverse code pulses to track section 1T during the off pulses of the normal code being supplied to track section 1T at the intermediate signal location.

The apparatus arrangement shown in the drawings has now returned to its normal condition with signals 1EG and 2EG cleared for eastbound train movements.

From this description it is apparent that with apparatus of my invention as shown in the drawings, I have provided an arrangement at an intermediate signal location whereby normal and reverse codes received in either direction are distinguished from each other, and the proper traffic controlling devices or signals are operated by the receipt of the normal code only.

Although I have herein shown and described only one form of apparatus embodying my invention, it will be understood that various changes and modifications may be made therein within the scope of the appended claims without departing from the spirit and scope of my invention.

Having thus described my invention, what I claim is.

1. In a railway traffic control system for a stretch of railway track extending between a first location and a second location and comprising two adjoining track sections over which traffic may at times move in a first direction and at other times move in a second direction opposite to said first direction, the combination comprising, an intermediate location in said stretch at the junction of said first and second track sections, means for supplying for said first direction of traffic normal code pulses of energy to the rails of said second track section at said second location, a first code following relay connected to the rails of said second track section at said intermediate location, a first slow release relay at said intermediate location, means controlled by said code following relay for picking up said slow release relay when the code following relay is following normal code pulses of energy, means controlled by said slow release relay in its picked up position for supplying normal code pulses of energy to the rails of said first track section at said intermediate location, a code following relay connected to the rails of said first track section at said first location, means operating to supply reverse code pulses of energy to the rails of said first track section at said first location during the off periods of the normal code pulses of energy received from said rails by said code following relay at said first location, a second code following relay connected to the rails of said first track section at said intermediate location, a second slow release relay at said intermediate location, means for supplying for said second direction of traffic normal code pulses of energy to the rails of said first track section at said first location, means controlled by said second code following relay at said intermediate location for picking up said second slow release relay when the code following relay is following normal code pulses of energy, a third slow release relay at said intermediate location, means controlled by said second slow release relay in its picked up position and said first code following relay at said intermediate location in its released position for picking up said third slow release relay, means controlled by said third slow release relay in its picked up position for maintaining said first slow release relay released, means controlled by said second and third slow release relays both in their picked up position for supplying normal code pulses of energy to the rails of said second track section at said intermediate location, a code following relay connected to the rails of said second track section at said second location, means operating to supply reverse code pulses of energy to the rails of said second track section at said second location during the off periods of the normal code pulses of energy received from said rails by said code following relay at said second location, means for supplying a code pulse of energy of a longer duration than a normal code pulse

of energy to the rails of said second track section at said second location when said direction of traffic is changed from said second direction to said first direction, and means controlled by said first code following relay at said intermediate location in its picked up position in response to said code pulse of energy of a longer duration for releasing said third slow release relay at said intermediate location.

2. In a railway traffic control system for a stretch of railway track including first and second adjoining track sections electrically insulated from each other and through which traffic moves in that order for a first direction of traffic between first and second locations in the stretch and in the opposite order for a second direction of traffic between said locations, the combination comprising; means for supplying to the rails of the second section at said second location normal code pulses for said first direction of traffic, reverse code pulses for said second direction of traffic, and a code pulse of a longer duration than a normal code pulse for changing the direction of traffic from the second direction to the first direction; means for supplying to the rails of the first section at said first location normal code pulses for said second direction of traffic and reverse code pulses for said first direction of traffic, first and second code responsive devices connected across the rails of said first and second track sections respectively at the junction of the sections; first, second, and third slow release relays at said junction; means controlled by said first device and said second relay for energizing said first relay only when the first device is energized by code pulses received from the rails of the first track section and the second relay is released, means controlled by said first and second relays for energizing said third relay when the first relay is energized and the second relay is released, means controlled by said third relay and said second device for energizing said second relay only when the third relay is released and the second device is energized by code pulses received from the rails of the second track section; and means controlled by said second device, in response to said code pulse of a longer duration, for deenergizing said third relay following a period of energization thereof.

3. In a railway traffic control system for a stretch of railway track including first and second adjoining track sections electrically insulated from each other and through which traffic moves in that order for a first direction of traffic between first and second locations in the stretch and in the opposite order for a second direction of traffic between said locations, the combination comprising, means for supplying to the rails of the first section at said first location reverse code pulses for said first direction of traffic and normal code pulses for said second direction of traffic; means for supplying to the rails of the second section at said second location reverse code pulses for said second direction of traffic, normal code pulses for said first direction of traffic, and a code pulse

of a longer duration than a normal code pulse to effect a change in the direction of traffic from said second direction to said first direction; first and second code following devices connected across the rails of said first and second sections respectively at the junction of the sections; first, second, and third slow release relays at said junction; means controlled by said second relay in its released position and by said first device in its code following condition for energizing said first relay, means controlled by said third relay in its deenergized position and said second device in its code following condition for energizing said second relay, means controlled by said first relay in its energized position and said second relay in its released position for energizing said third relay; and means controlled by said second device, energized in response to the receipt of said pulse of a longer duration, for deenergizing said third relay following a period of energization of that relay.

4. In a railway traffic control system for a stretch of railway track including first and second adjoining track sections electrically insulated from each other through which traffic moves in that order for a first direction of traffic and in the opposite order for a second direction of traffic, the combination comprising, means for supplying to the rails of said first track section at the entrance end thereof for said first direction of traffic reverse code pulses and at the exit end thereof for said second direction of traffic normal code pulses; means for supplying to the rails of said second track section at the entrance end thereof for said second direction of traffic reverse code pulses; at the exit end thereof for said first direction of traffic normal code pulses, and at the entrance end thereof for said second direction of traffic a code pulse of a longer duration than a normal code pulse when it is desired to change the direction of traffic from the second direction to the first direction; first and second code responsive devices connected to the rails of said first and second track sections respectively at the junction thereof; first, second, and third relays at said junction; means controlled by said first device and said second relay for energizing said first relay when the device responds to code pulses received from the rails of the first track section and the second relay is released, means controlled by said first and second relays for energizing said third relay when the first relay is energized and the third relay is released, means controlled by said third relay and said second device for energizing said second relay only when the third relay is released and the second device responds to code pulses received from the rails of the second track section; and means controlled by said second device for deenergizing said third relay, following a period of energization thereof, when the second device responds to said code pulse of a longer duration.
